UNITED STATES PATENT OFFICE.

JOSEPH H. BAST, OF SANTA MONICA, CALIFORNIA.

METAL FEEDER FOR LINOTYPE MACHINES.

Application filed May 31, 1923. Serial No. 642,642.

To all whom it may concern:

Be it known that I, JOSEPH H. BAST, a citizen of the United States, residing at Santa Monica, in the county of Los Angeles 5 and State of California, have invented new and useful Improvements in Metal Feeders for Linotype Machines, of which the following is a specification.

My invention is a metal feeder for linotype machines, and it is a special object of this invention to provide means for maintaining a substantially constant level of molten metal, as required in the casting of successive lines of type, in a well known 15 manner.

It is an object of this invention to provide means for suitably supporting a replenishing bar of type metal above a pot of the character described, and in a preferred embodiment of my invention I provide means for intermittent release and advance of the replenishing bar, this advance being made dependent upon the rate of withdrawal of molten metal.

It is a specific object of this invention to provide means whereby the normal reciprocation of a moving part, such as the reciprocation of a pump piston rod, may be utilized to trip a lock which normally holds a bar 25 of type metal in an elevated position; and in a preferred embodiment of my invention I may employ a float, upon one arm of a lever whose other or remote arm may be adapted to push a hook or the like, into the path of the mentioned reciprocating part, in such manner as to complete a release of a bar of type metal, whenever the mentioned float shall descend below a predetermined level.

Other objects of my invention will appear in the following description of a preferred embodiment thereof, and from the appended claims, taken in connection with the accompanying drawings, in which—

Fig. 1 may be regarded as a front elevation of a metal feeder of my preferred design, and the same being shown as extending into a pot which is shown in section.

Fig. 2 is a corresponding elevational view, 50 which may be regarded as taken at right angles to Fig. 1, the float and replenishing bar being shown in their respective lowered positions.

Fig. 3 is a view similar to Fig. 2, but 55 showing the replenishing bar and the float as in their respective elevated position.

Fig. 4 is a detailed view on an enlarged scale showing preferred type of lock, hereinafter described.

Figs. 5 and 6 show, respectively, vertical 60 and horizontal sections of securing means by which a bar of type metal may be secured to a supporting rod; Figure 6 being taken on the line 6—6 of Figure 5.

Fig. 7 shows an alternative form in which 65 a spacer block S is employed to keep a replenishing bar from contact with the bottom of a pot.

Referring in detail to that specific embodiment of my invention which I have 70 chosen for purposes of illustration, 1 is a pot, heated by any suitable means (not shown) in order to provide molten metal for the casting of linotype slugs or the like, such molten metal being forced, or pumped, 75 from said pot by means of a piston 2, whose rod 3 may be reciprocated by a lever 4, the said rod and lever being shown as connected by a pin 5, participating in the reciprocation of the rod 3, and preferably provided with 80 an extending end adapted to be engaged by a hook 6, for the purpose hereinafter described.

In order to introduce metal into the pot 1, as required to maintain a substantially 85 constant level therein, various means might be employed, but I propose, for this purpose, the use of a solid replenishing bar 7 of type metal, this being shown as removably connected to a vertical rod 8, which is adapted 90 to be held by a locking lever 9, except when a pull upon the link 10, pivoted thereto, shall cause a momentary release of the rod 8, and permit a descent of the mentioned 95 replenishing bar into the pot 1, with whose bottom it may then come in contact, as best shown in Figures 1 and 2.

In order to release the locking lever 9 by a suitable pull upon the link 10 whenever the molten metal in the pot 1 shall fall below a predetermined level, any suitable means may be employed; but, for this purpose, I propose to employ a float 11, which may be formed of a suitable infusible metal lighter than type metal, such as iron, this 100 float being shown as secured to the inner arm of a lever 12, pivoted at 13 upon the pot 1, the remote arm 14 of the said lever being provided with a loop or eye 15, adapted to engage and position the lower end of the 105 mentioned link 10, provided with the hook 6, it being obvious from an inspection of 110

the figures that when the float 11 descends below a predetermined level, corresponding movement of the loop 15 may bring the hook 6 into contact with the reciprocating pin 5, thereby causing such a pull upon the link 10 as shall move the lever 9 out of locking engagement with the rod 8, thereby permitting a descent of the replenishing bar 7 into contact with the bottom of the pot 1, in such manner that the lower end of the bar 7 will be melted and raise the level of the molten metal therein. Upon the mentioned raising of the level of molten metal in the pot 1, it will be obvious that, by the upward or return movement of lever 12, this movement being transmitted through the arm 14 carrying the loop 15, the hook 6 may be moved from the path of reciprocating pin 5, and the link 10 and lever 9 may thereby be permitted to return to their elevated, or normal, positions.

It will be obvious that any equivalent locking or clamping means might be substituted for those described, and that the return of the lever 9 to its locking position may be effected by any suitable means, such as a resilient element or spring 16, shown as secured under tension between the outer end of the lever 9 and a bracket 17, extending to the slide 18, carried by a fixed arm 19, to which it may be removably secured by means such as the bolt 20, the lever 9 being preferably provided with an eccentric or similar engaging surface 21 adjacent its pivot 22, extending through the guide 18 in such manner that the spring 16 may be effective to clamp the rod 8 relatively to the guide 18 whenever the hook 6 shall be disengaged from the pin 5, in the manner described.

Although any suitable means may be employed to connect a bar of type metal with the rod 8, or its equivalent, I suggest, for this purpose, the employment of a channel best seen in Figures 5 and 6, wherein it is shown as riveted to the bar 8 and provided with a projection 25, adapted to extend through a corresponding aperture 26 in the bar 7, the projection 25 being shown as provided with a threaded aperture within which is seated a thumb screw 27, having shoulder 28, adapted to contact with a washer 29 in such manner as to retain the bar 7 in contact with the interfitting flaring walls 30 of the channel member 24.

Although I have herein described but one complete embodiment, it will be understood that various features thereof might be independently employed, and also that various modifications might be made therein without departure from the spirit and scope of my invention, as the same is indicated above and in the following claims.

What I claim is:

1. A pot for molten type metal, means for

65 withdrawing metal therefrom, and means for maintaining a substantially constant level of molten metal therein, said maintaining means comprising a float pivoted on said pot and constituting an inner arm of a lever provided with means to position a hook 70 in the path of a reciprocating part.

2. A pot for molten type metal, means for withdrawing metal therefrom, and means for maintaining a substantially constant level of molten metal therein, said maintaining means comprising a float pivoted on said pot and constituting an inner arm of a lever provided with means to position a hook in the path of a reciprocating part connected 75 with a pump.

3. A pot for molten type metal, means for withdrawing metal therefrom, means for maintaining a substantially constant level of molten metal therein, said maintaining means comprising a guide for a movable support for a body of type metal, said guide being provided with a locking member, and a resilient means for moving said locking member into engaging position.

4. A pot for molten type metal, means for withdrawing metal therefrom, and means for maintaining a substantially constant level of molten metal therein, said maintaining means comprising a guide for a movable support for a body of type metal, said guide being provided with a locking member, and a link for moving said locking means.

5. A pot for molten type metal, means for withdrawing metal therefrom, and means for maintaining a substantially constant level of molten metal therein, said maintaining means comprising a guide for a movable support for a body of type metal, said guide being provided with a locking member, and a link for moving said locking means, said link being provided with a hook.

6. A pot for molten type metal, means for withdrawing metal therefrom, means for maintaining a substantially constant level of molten metal therein, said maintaining means comprising a guide for a movable support for a body of type metal, and comprising also a float, and means movable thereby for positioning a hook in the path of a reciprocating part.

7. A pot for molten type metal, means for withdrawing metal therefrom, means for maintaining a substantially constant level of molten metal therein, said maintaining means comprising a guide for a movable support for a body of type metal, and comprising also a float, and means movable thereby for positioning a hook in the path of a reciprocating part comprised in a pump.

In testimony whereof I have signed my name to this specification.

JOSEPH H. BAST,
